CLAIM

The ornamental design for a balcony as shown and described.

DESCRIPTION

FIG. 1 is an upper right front perspective view showing my new design;

FIG. 2 is a front elevational view thereof;

FIG. 3 is a right side elevational view thereof;

FIG. 4 is a rear elevational view thereof;

FIG. 5 is a left side elevational view thereof;

FIG. 6 is a top plan view thereof;

FIG. 7 is a bottom plan view thereof;

FIG. 8 is an enlarged partial upper right front perspective view thereof taken along line 8-8 of FIG. 1;

FIG. 9 is an enlarged partial front elevational view thereof taken along line 9-9 of FIG. 2;

FIG. 10 is an enlarged partial right side elevational view thereof taken along line 10-10 of FIG. 3;

FIG. 11 is an enlarged partial upper right front perspective view thereof taken along line 11-11 of FIG. 1;

FIG. 12 is an enlarged partial front elevational view thereof taken along line 12-12 in FIG. 2;

FIG. 13 is an enlarged partial right side elevational view thereof taken along line 13-13 in FIG. 3;

FIG. 14 is an enlarged partial upper right front perspective view thereof taken along line 14-14 in FIG. 1;

FIG. 15 is an enlarged partial right side elevational view thereof taken along line 15-15 in FIG. 3; and,

FIG. 16 is an enlarged partial rear elevational view thereof taken along line 16-16 in FIG. 4.

The broken lines shown in FIGS. 1-7, 9, 12, and 14-16 represent environment and portions of the balcony that form no part of the claimed design. The heavy, numbered broken lines in FIGS. 1-3 and the broken line outer edges in FIGS. 8-16 show the boundaries of the enlarged, partial views and also form no part of the claimed design.
